EXTENSIBLE HANGER FOR CLOTHES

Martin L. Lee, Brooklyn, N. Y.

Application June 24, 1931. Serial No. 546,554

12 Claims. (Cl. 312—176)

My invention relates to hangers for clothes particularly adapted for installation in trunks, closets or the like and the same has for its object to provide a simple, reliable and efficient arrangement which may be readily extended and collapsed; and which allows the clothes to be readily placed in position or removed without disarranging or wrinkling other garments on the racks.

10. Another object of the invention is to provide an arrangement of the character specified in which the racks thereof are adapted to slide in and out as a unit and also to be individually moved relative to each other for facilitating the insertion of removal of the garments.

Another object of the invention is to provide an arrangement of the character specified in which the rack supporting means thereof is readily detachable and is adapted to be mounted 20 either in a trunk or on a wall, as in a closet, as desired.

Another object of the invention is to provide an arrangement of the character specified in which the racks, when the device is extended, are capable of being individually swung apart without interference from the parts normally supporting the free ends thereof.

Another object of the invention is to provide an arrangement of the character specified in 30 which the racks may be readily interengaged with the support therefor to prevent relative movement of the racks in the collapsed condition of the device.

Other objects will in part be obvious and in 35 part be pointed out hereinafter.

In the accompanying drawings:

Figure 1 is a perspective of one form of device constructed according to and embodying my said invention, the same being shown applied to a 40 trunk and in extended position;

Fig. 2 is a section thereof on the line 2—2 of Fig. 1;

Fig. 3 is a plan thereof with parts in section, the device being shown in collapsed position;

Fig. 4 is a section on the line 4—4 of Fig. 3;

Fig. 5 is a similar view showing the parts in projected or extended position;

Fig. 6 is a section on the line 6—6 of Fig. 3;

Fig. 7 is a perspective of the means for pivotally supporting the racks; and

Fig. 8 is a perspective of a fixture or bracket for supporting the device shown at Fig. 7 from a wall.

55 Referring to the drawings, I have illustrated my novel arrangement or device applied to a

trunk 10, having a top cover 12 and front cover 14. The interior of the top portion of the trunk is reinforced by a U-shaped metallic strip 16 serving as support for the tubular tracks or guideways 18 and 20 extending along the opposite sides 60 of the trunk. The guideway 18 is preferably permanently secured to the supporting strip 16, the latter being provided with inturned front end 22 for supporting the front end of the guideway 18. The guideway 20 is preferably made detachable 65 and is provided at the rear end thereof and at one side with downwardly extending tongues 24, 26 and 28 adapted to be received into pockets or openings 30, 32 and 34 suitably formed in the strip 16, whereby to rigidly support the track 20 70 in position. The attaching members 26 and 28 are preferably bifurcated at the lower ends, as indicated at 36, for receiving the shanks of set screws 38 threaded into the strip 16 and adapted to be tightened to clamp the tongues 26 and 28 75 against the strip.

Both tubular track members or guideways 18 and 20 are open at their forward ends at 40 and 42, and at the upper sides thereof are provided with longitudinal slots 44 and 46 substantially 60 coextensive in length therewith.

Trolley members 48 and 50 are slidably received within the guideways 18 and 20 for movement in and out, through the open ends 40 and 42 thereof, said trolley members being of slightly greater length than said guideways and adapted to be received within the latter in the collapsed or retracted position of the device. The guideways 18 and 20 and trolley members 48 and 50 are preferably non-circular, and the trolley members are preferably provided with longitudinal ribs 52 and 54 projecting into the slots 44 and 46, whereby to retain the trolley members against rotation and provide clearance above the guideways for the hangers or racks 56. The several racks 56 are each provided at one end with a vertical pintle 58 detachably received into any of a series of longitudinally spaced holes 60 formed in the rib 54 of the member 50. The opposite ends of the racks are provided with notched portions 62 adapted to interengage or to be hooked into any of a longitudinal series of recesses or notches 64 formed in the rib 52 of the trolley member 48, whereby to retain the several racks in uniformly spaced relation in the closed position 95 of the device without the hanger ends being liable to slide out of place.

The trolley member 48 is preferably made in two sections 66 and 68 hinged together at 70 so that when the member is pulled out the front 110

section 66 can drop down out of the way and disengage the racks 56. A dog 72 is pivotally connected to the rear section 68 within a recess therein and is adapted to enter a slot 74 in the 5 guideway 18 to act as stop to prevent member 48 from being entirely withdrawn from its guideway. Upon backward movement of the member 48 the dog 72 is lifted by engagement with the lower portion of the guideway 18 to allow free 10 movement to retracted position. At Fig. 8 is shown a bracket or fixture 76 adapted to be secured to a wall, such as in a closet, and provided with tongue receiving pockets or slots 30^a, 32^a and 34^a similar to those formed in the strip 16 15 and adapted to receive and support the track member 20 together with the slide 50 and racks 56 when the assembly is transferred from a trunk to the closet for supporting the garments outside of the trunk. The member 76 is also provided with set screws 38^a for engaging the bifurcated ends of the tongues 26 and 28 when the member 20 is attached to said bracket 76.

The device may be readily pulled out from the position shown at Fig. 3 by grasping the knobs 78. When the member 48 is pulled out sufficiently to allow the section 66 to drop down, the several hangers 56 supported by their pintles 58 may be swung or fanned out relative to each other, as shown at Fig. 1, to allow the clothes or garments 30 to be readily removed or placed in position without wrinkling the garments on contiguous hangers or racks and without the insertion or removal of any garment being interfered with because of the presence of contiguous garments. Upon retraction of the device, the front section 66 is brought into alignment with the guideway 18 and the several hangers 56 hooked into the notches 64 and retained thereby in fixed spaced apart relation. When desired the clothes or garments 40 can be readily transferred from the trunk to a closet or the like by detaching the member 20 and hooking the same to a bracket such as 76.

Having thus described my invention, what I 45 claim and desire to secure by Letters Patent is:

1. A device of the character described comprising racks, and plural extensible means in spaced relation for supporting said racks at the ends, one of said extensible means pivotally supporting said racks for swinging movement horizontally, and the other of said extensible means including provision for disengaging the racks in the projected positions of the several extensible means to allow said swinging movement of the 55 racks.

2. A device of the character described comprising extensible members, and racks each pivotally supported at one end by one of said members for swinging movement horizontally, said racks being supported at the opposite ends by the other of said members, and said racks and said last named member having interengaging portions to retain the free ends of the racks in place on said last named member.

3. A device of the character described comprising a support having open portions, a guide member having tongues received into said open portions, a trolley member slidably supported by said guide member and having a series of longitudinally spaced apart holes in the top thereof, and racks each having a vertical pintle at one end received into said holes for pivotally supporting the racks.

4. A device of the character described comprising a pair of tubular track members having lon-

gitudinal slots at the upper sides thereof, trolley members slidably received within said track members and having portions projecting through said slots, and a plurality of garment supporting members pivotally connected to the projecting portion of one of said trolley members and adapted to engage the projecting portion of the other trolley member to be supported at the free ends thereby.

5. A device of the character described comprising track members, trolley members adapted to slide thereon, one of said trolley members having a longitudinal series of holes therein and the other trolley member having a longitudinal series of recesses therein, and a plurality of garment supporting members having end portions received into said holes for pivotal movement, and hooked portions at the opposite ends adapted to engage said recesses.

6. A device of the character described comprising a pair of extensible members, one of said members having a series of holes therein at the upper side, and the other extensible member including jointed portions having recesses at the upper side thereof, means for retaining the jointed portions in alignment in the retracted position thereof, and a plurality of racks having pintles at one end received into said holes for pivotal movement and having hooked portions at the opposite ends adapted to engage said recesses, said jointed member in the extended position thereof dropping out of the way to allow free swinging movement of said racks.

7. A device of the character described comprising a pair of tubular tracks having longitudinal slots at the upper sides thereof, trolley members sliding within said tracks and having portions projecting through said slots, one of said trolley members including hinged portions adapted to be retained in alignment by the track therefor in the retracted position thereof and allowing the forward portion to drop down in the extended position thereof, and a plurality of garment supporting members pivotally connected at one end to the projecting portion of the other trolley member at longitudinally spaced points thereon and adapted to be supported at the opposite ends by the projecting portion of the hinged trolley member.

8. A device of the character described comprising a pair of tracks, trolley members slidable on said tracks, one of said trolley members including hinged sections adapted to be retained in alignment by the track therefor in the retracted position thereof and allowing the front section to drop down in the extended position thereof, and a plurality of racks pivotally connected to the other trolley member at spaced points therealong and adapted to be supported at the free ends by the hinged trolley member in the retracted position thereof, the free ends of said racks and said hinged trolley member having interengaging portions to retain the racks in spaced apart relation at the free ends thereof.

9. A device of the character described comprising a pair of tracks, trolley members slidable on said tracks, one of said trolley members including hinged sections adapted to be retained in alignment by the track therefor in the retracted position thereof and allowing the front section to drop down in the extended position thereof, and a plurality of racks pivotally connected to the other trolley member at spaced points therealong and adapted to be supported at the free ends by the hinged trolley member in the retracted posi-

tion thereof, the free ends of said racks and said hinged trolley member having interengaging portions to retain the racks in spaced apart relation at the free ends thereof, and means for stopping the forward sliding movement of the hinged trolley member at a point where the forward section is free to drop.

10. The combination with a cabinet having a reinforcing member secured about the back and sides at the inside thereof adjacent the top, of a pair of tracks secured to said reinforcing member, trolley members sliding on said tracks, and a plurality of garment supporting members pivotally connected to one of said trolley members 15 and having the free ends thereof adapted to be supported by the other trolley member.

11. The combination with a cabinet having a reinforcing member secured about the back and sides at the inside thereof adjacent to the top, 20 of a pair of tracks secured to said reinforcing member, one of said tracks and said reinforcing member having portions interengaging to render the track detachable, trolley members slidable on said tracks, the trolley member of the detachable track having a series of holes therein, and the

other trolley member including hinged portions retained in alignment by the track thereof in the retracted position thereof, the forward hinged portion being free to drop in the extended position thereof, and a plurality of racks having 80 pivot portions received in said holes, and adapted to be supported at the free ends by the hinged trolley member in the retracted position thereof, the free ends of the racks and the hinged trolley member having interengaging portions to retain 85 the free ends of the racks in position.

12. A device of the character described comprising a pair of tracks, trolley members slidable on said tracks, one of said trolley members including hinged sections adapted to be retained in alignment by the track therefor in the retracted position thereof, and allowing the front section to drop down in the extended position thereof, and a plurality of racks pivotally connected to the other trolley member at spaced points therealong 95 and adapted to be supported at the free ends by the hinged trolley member in the retracted position thereof.
